UNITED STATES PATENT OFFICE.

MARK M. HENDERSON, OF NEW YORK, N. Y.

UNDERWEAR.

1,141,636.

Specification of Letters Patent. Patented June 1, 1915.

Application filed November 22, 1911. Serial No. 661,693.

To all whom it may concern:

Be it known that I, MARK M. HENDERSON, citizen of the United States, and resident of borough of Manhattan, in the city and county of New York and State of New York, have invented certain new and useful Improvements in Underwear, of which the following is a specification.

My invention relates to improvements in union suits and contemplates in the drawers portion of the garment a sanitary flap opening which fastens up at one side of the leg, and which, when closed, forms a complete covering for the rear parts.

In the drawing, the figure is an elevation of the complete suit as seen from the back, with the flap partly thrown open.

In producing my improved union suit, I provide in the drawers portion thereof a rear flap D which is disconnected from about the waist line downward to the end of one trunk or leg, said flap having a suitable fastening means such as buttons and button holes as shown at E whereby it may be fastened up against the outer side of the leg or unfastened therefrom to be free. When free, said flap may be turned back sufficiently for sanitary purposes. The front portion of the garment is of course provided with the usual opening down the center as shown at A.

I claim:

A union suit provided in one leg only with an opening extending down the outer side thereof from a point near the waist line through the lower end of the leg of the garment, and also provided with a second, independent opening, in the shirt portion extending from the neck to the crotch thereof.

Signed at borough of Manhattan, in the city and county of New York and State of New York this 25th day of July A. D. 1911.

MARK M. HENDERSON.
